E. A. ROCKWELL,
LIQUID FEEDING DEVICE,
APPLICATION FILED NOV. 21, 1919.

1,360,028.

Patented Nov. 23, 1920.

UNITED STATES PATENT OFFICE.

EDWARD A. ROCKWELL, OF FLUSHING, NEW YORK, ASSIGNOR TO E. A. ROCKWELL COMPANY, INC., OF NEW YORK, N. Y., A CORPORATION OF NEW YORK.

LIQUID-FEEDING DEVICE.

1,360,028.

Specification of Letters Patent. Patented Nov. 23, 1920.

Application filed November 21, 1919. Serial No. 339,591.

To all whom it may concern:

Be it known that I, EDWARD A. ROCKWELL, a citizen of the United States, residing at Flushing, in the county of Queens 5 and State of New York, have invented a certain new and useful Improvement in Liquid-Feeding Devices, of which the following is a specification.

My invention relates particularly to an 10 apparatus designed for feeding liquids of various kinds, but has special reference to apparatus designed for feeding liquid fuel to automobile engines.

The object of my invention is to provide 15 an apparatus by means of which liquids of various kinds may be fed, but which is especially adapted for feeding fuels to internal combustion engines.

Another object of my invention is to provide 20 a feeding system of this character which is so constructed that a large volume of fuel may be fed. Again the object of my invention is to provide an apparatus in which there is a vacuum tank, or chamber 25 adapted to be supplied with fuel by means of the vacuum of the internal combustion engine with which it is connected, said vacuum tank being arranged to discharge very rapidly into an auxiliary supply tank 30 or chamber through an opening normally closed by a valve which may be readily unseated by means of a relatively small force exerted thereon. Another object of my invention is to provide a simple construction 35 of this character which may be manufactured at a minimum cost. Still another object of my invention is to provide an apparatus in which the degree of vacuum applied is maintained substantially constant irrespective of different engine speeds and different degrees of vacuum applied by the engine at different times, so as to obtain thus a uniformity in operation of the apparatus, and increase the volume of fuel which may 45 be carried by the vacuum tank owing to the small size of the operating float contained therein. The object of my invention is, furthermore, to in this way provide a feeding system which has sufficient capacity and 50 speed of operation to supply engines of large horse power, as for example engines used for driving heavy motor vehicles.

A further object of my invention is to 55 make possible even a greater economy in construction and also even a greater reliability of operation than is possible by the

use of the system for feeding by means of a vacuum described and claimed in my application Serial No. 301,827, filed June 4, 1919, the present invention being essentially 60 an improvement upon the organization therein described and claimed, although certain features of novelty herein described and claimed may be capable of numerous 65 independent uses.

While my invention is capable of embodiment in many different forms, for the purpose of illustration I shall show only one form of my invention in the accompanying drawings, in which:

Figure I is a vertical section of an apparatus made in accordance with my invention.

Fig. II is a partial section taken on the line II-II of Fig. I, looking downward. 75

In the drawings, I have shown a vacuum tank or chamber 1, which may be connected by means of a pipe 2 to a main supply tank for fuel, such as gasolene, and which may be connected also by a pipe 3, having a small 80 port 3^a, to the intake manifold of an internal combustion engine, such for example as an automobile engine. The discharge end of the pipe 2 may be screwthreaded in a sleeve 3^b which may have a groove 3^c to receive a ring 3^d which may hold in place a screen 3^e, so as to prevent the entry of dirt 85 into the apparatus. The lower free edge of the chamber 1 may have a shouldered flange 4 which fits over the top or separating plate 90 of an auxiliary supply tank or chamber 5 and may be secured thereto by means of screws 6. Said auxiliary supply tank 5 may have a bottom closure 7 which may be connected by a pipe 8 to the carburetor of the 95 internal combustion engine above referred to. A pipe 9 may extend upwardly from the top of the tank 5 through the chamber 1, and out through the top of the latter through a socket 10. The exterior of the socket 10 100 may be screwthreaded to receive a hexagonal cover 11 which maintains a packing around the upper end of the vent pipe 9, and which may have a circular cap 13 secured to the top of the cover 11, so as to allow spaces 14 105 at intervals around the cap 13 through which air may pass. In the interior of the tank or chamber 1 there may be a bracket 15 which may be secured to the vent pipe 9 for guiding a rod 16 which projects upwardly from a float 17, made of any desired material, but preferably balsa wood. The 110

rod 16 may be extended below the float 17 where it may be pivoted to a lever 19. This lever 19 may have at its other end a link 20 which may connect it to an arm 21 attached 5 to one side of a valve closure 22 adapted to fit against the under side of a valve seat which may be a ground flat surface terminating a collar 23 carried in an aperture in the top of the tank 5. In the preferred 10 form of float-operated valve adapted for use in the present organization, lever 19 may have at one side a projection 24 to contact with a projection 25 on the link 20, so as to prevent lateral displacement of the valve 22 15 when it is being seated. In the initial opening movement of the valve 22 the lever 19 rotates, in this construction shown, upon a pivot 25^a by means of which the lever 19 is connected by a lever 25^b to a pivot 25^c on 20 the top of the tank 5. Afterward, however, the opening movement of the valve 22 is completed by the rotation of the lever around the pivot 25^c. The valve 22 in closing is moved by the lever 19 on the pivot 25^a as a fulcrum. At the top of the lever 25^b there may be a stop 25^d which limits the movement thereof relative to the lever 19, and at the bottom of the lever 25^b there may be a stop 25^e between which and the top of 30 the tank 5 there is normally a slight clearance to permit the valve 22 to be closed tightly by the vacuum applied to the top thereof; but this clearance is removed at the beginning of the opening movement of the 35 valve 22 when the liquid begins to rise in the tank 5.

Within the mentioned collar 23 (which may be secured in any suitable manner, as by mere driving or soldering into an opening 40 in the top of tank 5) and extending nearly, but preferably not quite to the bottom thereof, there may be inserted a pipe 33, secured therein in any convenient manner, as by forcing, within said collar and 45 against said pipe, a securing ring, or the like 34, preferably deformed to correspond very closely with the walls against which it must fit. Pipe 33 serves, as will be apparent, to permit a rise of gaseous materials simultaneously with the descent of liquid through pipe 33 whenever the valve closure 22 may be removed from its seat. The pipe 50 33, which may or may not contact with pipe 9, and may or may not be secured thereto, may be inserted at an inclination 55 corresponding to a taper in the collar 23, such taper serving to assure the firm seating of the ring 34 which may be split or entire, cast or stamped, and of uniform or varying 60 thickness and breadth—important consideration being the economy and permanence of the novel construction here referred to.

Within a second aperture in the mentioned top plate of the tank 5 there may also 65 be inserted, in any convenient manner, a

secondary valve, preferably of such character that it shall open automatically whenever the pressure in the vacuum chamber 1 shall fall, by any predetermined amount corresponding to an adjustment of the said 70 secondary valve, below the then existing pressure in auxiliary supply tank. Said secondary valve also obviates the necessity of having any expansion chamber present in connection with the tank 5, inasmuch as 75 the said secondary valve will always unseat itself whenever there is any undue increase of pressure in the tank 5 in case said pressure should accumulate while the valve 22 is closed. In this way, any possibility of the 80 fuel boiling out through the vent pipe 9 due to any increase in pressure in the tank 5 is entirely avoided. In the form of my invention herein illustrated, this secondary valve comprises a body 35, so bored that the shaft 85 of a plunger 36 shall move freely therein, within the limits fixed by the head 37 and the adjusting nut 38. Between nut 38 and the body 35, which may contain openings 39, may be compressed a spring 40, adapted 90 to close the valve by drawing the face 41 against the correspondingly beveled face 42. The auxiliary tank 5 being open to the outer air through pipe 9, it is the function of the secondary valve organization just described 95 to set a maximum to the difference in pressure that may exist between chamber 5 and the vacuum feed chamber 1; for whenever the suction through pipe 3 might become so strong as to interfere with the reliable action 100 of the float-controlled valve system above described, the ingress of air through pipe 9, and thence through the secondary valve, will serve to reduce to a desired maximum (dependent on the adjustment of said secondary valve) the "suction" that must draw fuel through pipe 2, but that inevitably tends also to hold the mentioned float-operated valve in its closed position. The secondary valve organization herein described, 105 operating regardless of any movement between the two chambers herein mentioned, serve a function somewhat analogous to that of a valve placed on the top of the vacuum chamber 1 in the device of my former application above referred to, but it presents very notable advantages in simplicity of construction, reliability of operation, and reduced liability to derangement through introduction of dust, accidental damage, or 110 otherwise.

In its present position the valve is self-cleaning and introduces only dust-free gaseous materials; and it is out of reach of tampering or misdirected attention. 115
The chamber 1 and the tank 5 may be supported by means of a bracket 26^a surrounding the lower portion of the tank 5, which bracket may have an upwardly-directed tongue 27 adapted to be secured by screws 28 120 125

to the dash board or any other part of an automobile. Welded or otherwise secured to the top of the tongue 27 there may be a metal strap 29 having at one end thereof a hook 30 for engagement with a yoke 31 connected by a square ring 32 to a loop on the other end of the strap 29, the details here referred to being fully described in my mentioned prior application, Serial Number 10 301,827.

In the operation of my invention, a supply of fuel, such as gasoline, having been introduced into the main supply tank which may be at a lower level than the auxiliary supply tank 5, as for example at the lower rear portion of an automobile, and the engine having been started so as to intermittently form a vacuum in the vacuum chamber 1 through the port 3^a, the fuel will be drawn from the main supply tank by means of the pipe 2, and discharged into the vacuum chamber 1, as shown in Fig. 1, which indicates the position of the parts when the valve 22 is closed. Inasmuch as the valve 22 is retained closed by the vacuum which is in the vacuum chamber 1, as well as the weight of the float 17, the level of the liquid fuel will rise in the chamber 1 until the liquid level reaches a point on the upper portion of the float 17 whereupon a sudden lifting effort of considerable strength will be applied to the rod 16 which will first cause the stop 25^a to contact with the top of the tank 5, and then depress the side of the valve 22 to which the arm 21 is attached. This will unseat the valve 22, although the valve 22 is of such large area that the buoyancy of a float in the chamber 1 would not be sufficient to open the valve 22 against the force of the vacuum holding the same closed if the link 20 were connected to the center of the valve. In this way a powerful leverage acts by means of the lever 19 to initially open the valve 22. Once the valve 22 is unseated in this manner, the vacuum will be broken and the lever 19 will then change its center of rotation from the pivot 25^a to the pivot 25^c, so as to entirely open the valve 22, and permit the quick discharge of a large volume of liquid from the chamber 1 into the tank 5. The opening of the valve 22 is completed with the aid of the force of gravity. In this way, a constant supply of fuel will be provided in the auxiliary tank 5, and the fuel will flow therefrom into the carburetor, whence the mixed air and gasoline will be supplied to the internal combustion engine. In the closing movement of the valve 22, it will be understood that the lever 19 will rotate upon the pivot 25^c until the valve 22 is closed, the valve being closed very quickly because of the long leverage with which it is operated. Whenever the valve 22 is closed, there will be a vacuum again developed in the tank 1, but

this vacuum will be of a uniform character because of the fact that at every suction stroke of the engine piston, or as often as may be necessary, the mentioned secondary or vacuum release valve between vacuum chamber 1 and auxiliary tank 5 will open to an extent depending on the degree of vacuum applied by the engine. As mentioned, the presence of this secondary valve also decreases the vacuum which is applied to the upper side of the valve 22, and consequently renders it possible to open said valve with a very much smaller lifting effort of the float than would otherwise be the case. For this reason, the float 17 is made smaller than would otherwise be possible, and smaller than would unseat the valve 22 if the described secondary valve, or its equivalent, were absent. The capacity of the tank 5 is, therefore, correspondingly greater, and this as well as the valve construction which permits a rapid feed of the fuel permits the use of my feeding system in connection with high powered engines. By constructing the apparatus in this manner, furthermore, the vacuum feed will be just as effective when there is a very low vacuum produced by the engine as when there is a normal vacuum or a high vacuum produced. The presence of the valve 37 also prevents the possibility of gasoline boiling out through the vent pipe 9 due to any increase of pressure in the tank 5, which might accumulate if the valve 37 were not present. The uniform operation of the valve 22 is, furthermore, insured by the presence of the screen 3^e which prevents the entry of particles of dirt into the apparatus. The tank 5 is at all times vented to the outer air through the vent pipe 9. Whenever it is desired to repair the apparatus in any manner, it can readily be removed by disengaging the yoke 31 from the hook 30, bending the ends of the strap 29 apart, and disconnecting the pipes 2, 3 and 8 from the chamber 1 and the tank 5.

While I have described my invention above in detail, I wish it to be understood that many changes may be made therein without departing from the spirit thereof.

I claim.

1. In combination, a vacuum chamber, an auxiliary chamber, a separating plate therebetween, said separating plate being provided with a plurality of apertures, a pressure operated valve in one of said apertures 120 and a float-operated valve in another of said apertures.

2. In combination, a vacuum chamber, an auxiliary chamber, a separating plate therebetween, said separating plate being provided with a plurality of apertures, a pressure-operated valve opening upward in one of said apertures, and a float-operated valve in another of said apertures.

3. In combination, a vacuum chamber, an

115

120

125

130

auxiliary chamber, a separating plate therebetween, said separating plate being provided with a plurality of apertures, a pressure-operated valve in one of said apertures 5 and a float-operated valve opening downward in another of said apertures.

4. In combination, a vacuum chamber, an auxiliary chamber, a separating plate therebetween, said separating plate being provided with a plurality of apertures, a pressure-operated valve opening upward in one 10 of said apertures, and a float-operated valve opening downward in another of said apertures.

15 5. In combination, a vacuum chamber, an auxiliary chamber, a separating plate therebetween, said separating plate having a plurality of ducts leading through said plate, through one of which a fluid may descend, 20 through another of which a fluid may ascend, and a single means for interrupting the passage of fluids through both of said ducts.

25 6. In combination, a vacuum chamber, an auxiliary chamber, a separating plate therebetween, said separating plate having a plurality of ducts leading through said plate, through one of which a fluid may descend, 30 through another of which a fluid may ascend, and means for simultaneously interrupting the passage of fluids through both of said ducts.

35 7. In combination, a vacuum chamber, an auxiliary chamber, a separating plate therebetween, said separating plate having a plurality of ducts leading through said plate, through one of which a fluid may descend, 40 through another of which a fluid may ascend, and means dependent on the level of the liquid in one of said chambers for interrupting the passage of fluids through both of said ducts.

45 8. In combination, a vacuum chamber, an auxiliary chamber, a separating plate therebetween, said separating plate having a plurality of ducts leading through said plate, through one of which a fluid may descend, 50 through another of which a fluid may ascend, and means dependent on the level of the liquid in one of said chambers for simultaneously interrupting the passage of fluids through both of said ducts.

55 9. In combination, a vacuum chamber, an auxiliary chamber, a separating plate therebetween, said separating plate being provided with a passageway through which a fluid may descend, said passageway having a conduit through which a fluid may ascend, and a single means for closing said 60 passageway.

10. In combination, a vacuum chamber, an auxiliary chamber, a separating plate therebetween, said separating plate being provided with a passageway through which a 65 fluid may descend, said passageway having

a conduit through which a fluid may ascend, and means extending across the bottom of said conduit for closing said passageway.

11. In combination, a vacuum chamber, an auxiliary chamber, a separating plate therebetween, said separating plate being provided with a passageway through which a fluid may descend, said passageway having a conduit through which a fluid may ascend, and means extending across the bottom of said conduit and dependent on the level of the liquid in one of said chambers for closing said passageway. 70 75

12. In combination, a vacuum chamber, an auxiliary chamber, a separating plate therebetween, said separating plate being provided with a passageway through which a fluid may descend, said passageway having a conduit through which a fluid may ascend, and means extending across the bottom of said conduit and dependent on the level of the liquid in said vacuum chamber for simultaneously closing said passageway. 80 85

13. In combination, a vacuum chamber, an auxiliary chamber, a separating plate therebetween, said separating plate being provided with a plurality of apertures, a pressure-operated valve in one of said apertures, a float-operated valve in another of said apertures, and a separate air intake located between the respective chambers. 90 95

14. In combination, a vacuum chamber, an auxiliary chamber, a separating plate therebetween, said separating plate being provided with a plurality of apertures, a pressure-operated valve opening upward in one of said apertures, a float-operated valve in another of said apertures, and a separate air intake located between the respective chambers. 100 105

15. In combination, a vacuum chamber, an auxiliary chamber, a separating plate therebetween, said separating plate being provided with a plurality of apertures, a pressure-operated valve in one of said apertures, a float-operated valve opening downward in another of said apertures, and a separate air intake located between the respective chambers. 110

16. In combination, a vacuum chamber, an auxiliary chamber, a separating plate therebetween, said separating plate being provided with a plurality of apertures, a pressure-operated valve opening upward in one of said apertures, a float-operated valve opening downward in another of said apertures, and a separate air intake located between the respective chambers. 115 120

17. In combination, a vacuum chamber, an auxiliary chamber, a separating plate therebetween, said separating plate having a plurality of ducts leading through said plate, through one of which a fluid may descend, through another of which a fluid may ascend, a single means for interrupting 125 130

the passage of fluids through both of said ducts, and a separate air intake located between the respective chambers.

18. In combination, a vacuum chamber, 5 an auxiliary chamber, a separating plate therebetween, said separating plate having a plurality of ducts leading through said plate, through one of which a fluid may descend, through another of which a fluid 10 may ascend, means for simultaneously interrupting the passage of fluids through both of said ducts, and a separate air intake located between the respective chambers.

19. In combination, a vacuum chamber, 15 an auxiliary chamber, a separating plate therebetween, said separating plate having a plurality of ducts leading through said plate, through one of which a fluid may descend, through another of which a fluid 20 may ascend, means, dependent on the level of the liquid in one of said chambers for interrupting the passage of fluids through both of said ducts, and a separate air intake located between the respective chambers.

20. In combination, a vacuum chamber, 25 an auxiliary chamber, a separating plate therebetween, said separating plate having a plurality of ducts leading through said plate, through one of which a fluid may 30 descend, through another of which a fluid may ascend, means dependent on the level of the liquid in one of said chambers for simultaneously interrupting the passage of fluids through both of said ducts, and a 35 separate air intake located between the respective chambers.

21. In combination, a vacuum chamber, 40 an auxiliary chamber, a separating plate therebetween, said separating plate being provided with a plurality of passages, 45 through one of which a fluid may descend, through another of which a fluid may ascend, a conduit through which a gaseous fluid may ascend, a closure capable of extending across the bottom of said conduit, and a separate air intake located between the 50 respective chambers.

22. In combination, a vacuum chamber, 55 an auxiliary chamber, a separating plate therebetween, said separating plate being provided with a plurality of passages, through one of which a fluid may descend, through another of which a fluid may ascend, a conduit through which a gaseous fluid may ascend, a closure capable of extending across one of said passages and across the bottom of said conduit, and a separate air intake located between the 60 respective chambers.

23. In combination, a vacuum chamber, 65 an auxiliary chamber, a separating plate

therebetween, said separating plate being provided with a plurality of passages, through one of which a fluid may descend, through another of which a fluid may 65 ascend, a conduit through which a gaseous fluid may ascend, a closure capable of extending across the bottom of said conduit and dependent on the level of the liquid in one of said chambers for closing one of said 70 passages, and a separate air intake located between the respective chambers.

24. In combination, a separating plate provided with an aperture, a collar within said aperture, a pipe within said collar, and 75 a closure capable of controlling movement of fluids through said aperture.

25. In combination, a vacuum chamber, 80 an auxiliary chamber, a separating plate therebetween, said separating plate being provided with an aperture, through which a fluid may descend, a closure for said aperture, means for admitting air to said auxiliary chamber, and additional means for conditionally effecting, regardless of any 85 movement of liquid between said chambers, a partial equalization of pressures therebetween.

26. In combination, a vacuum chamber, 90 an auxiliary chamber, a separating plate therebetween, said separating plate having a plurality of ducts leading through said plate, through one of which a fluid may descend, and additional means for conditionally effecting, regardless of any 95 movement of liquid between said chambers, a partial equalization of pressures therebetween.

27. In combination, a separating plate provided with an aperture through which a descending liquid and an ascending fluid 100 may simultaneously pass, a collar corresponding with said aperture, a pipe within said collar adapted for the ascent of the fluid, a securing ring in contact with both said collar and said pipe and providing a 105 separate passage for the descent of the liquid, and a closure controlling the movement of both said liquid and said fluid.

28. In combination, a separating plate provided with an aperture through which 110 fluids may pass, a tapered collar corresponding with said aperture, a pipe within said collar inclined in conformity therewith and adapted for the ascent of the fluid, a securing ring in contact with both said collar and 115 said pipe, and a closure controlling the movement of fluids through said aperture.

In testimony that I claim the foregoing, I have hereunto set my hand this 17th day of November, 1919.

EDWARD A. ROCKWELL.
